[57] CLAIM

The ornamental design for a display cover for hand held video game, as shown and described.

DESCRIPTION

FIG. 1 is a top perspective view of a display cover for hand held video game showing my new design; the broken line showing of a hand held video game is for illustrative purpose only and forms no part of the claim;

FIG. 2 is a right side elevational view thereof;

FIG. 3 is a rear elevational view thereof;

FIG. 4 is a bottom plan view thereof;

FIG. 5 is a left side elevational view thereof; and,

FIG. 6 is a front elevational view thereof.
